METHOD OF REACTIVATING
HYDROCARBONSSylvester Dayson, Baird, Tex., and
Jubal R. Parten, Shreveport, La.

Application December 22, 1932, Serial No. 648,326

1 Claim. (Cl. 196—96)

The invention relates to an improvement in processes of treating hydrocarbons and in the composition of products obtained by such processing.

- 5 It is one of the objects of the invention to provide a method of refluxing the polymers drawn off from the process of treating hydrocarbon oils and re-introducing such polymers into the stream of cracked oils entering the process.
- 10 Another object of the invention is to re-introduce the polymers from the process so that the gums of the polymers are combined with the tars of the crude entering the process and producing a superior grade of fuel oil.
- 15 Another object of the invention is to permit separation of the lighter and heavier fractions from the fractionating column and refluxing the heavier fractions into the top of the fractionating column to control the end point of the fractions issuing from the column.
- 20 Another object of the invention is to provide a method of making up a composite charge for treatment by mixing charges of cracked oils, reduced crude and hot polymers.
- 25 Another object of the invention is to provide a method of treating hydrocarbons wherein the heavier fractions are refluxed through the fractionating column and the hot polymers from the refectionator are re-introduced into the charge entering the process; and wherein also the lean oil drawn from the fractionating column is reintroduced into the absorber tower in order to absorb the gasoline from the gas being discharged from the system.
- 30 Other and further objects of the invention will be readily apparent when the following description is considered in connection with the accompanying drawing wherein:

Fig. 1 is a diagrammatic side view of a schematic arrangement of the various pieces of equipment which may be used in practicing the invention.

Various processes and pieces of equipment have been devised with a view of increasing the yield of gasoline obtainable from crude oil by the cracking and other processes. These methods and equipment have resulted in a material increase in the yield and in the quality of the fuel obtainable. With the present invention, however, it has been found that the yield may be further increased by resorting to various arrangements of the parts and refluxing some of the fluids.

Some of the principal contributions include the mixing of the hot polymers with the entering

charge, and the refluxing of the fractionating columns and the reactivating tower.

Reference may be had to the accompanying drawing, and particularly Fig. 1, where the schematic arrangement illustrates a pipe or conduit 2, through which a charge of cracked oils must flow in entering the system. This pipe may lead from any desired type of still wherein the crude oil has been cracked. In the processes now in general use, the temperature of the cracked charge through the pipe 2 approximates 950° F. Instead of directing this cracked charge from the pipe 2 directly into the fractionating column 3, the conduit 2 is led into what may be termed a mixing chamber 4. This chamber may take any desired form and it has merely been illustrated in elevation here as a housing or container. Connected to this mixing chamber 4 is another conduit 5, through which it is intended to introduce a charge of reduced crude oil. This charge of crude comes into the mixing chamber 4 at about 500° F. The fact that this reduced crude charge is cooler than the cracked charge tends to equalize the temperature of the two charges, so that they will not be entering the fractionating column at so high a temperature.

As is now well understood, the charge of fluid entering the fractionating column progresses through the process so that the lighter fractions are removed and the heavier fractions separated out as polymers. These polymers have heretofore been drawn off as a waste product. It is contemplated, in connection with the present invention, however, to reprocess these polymers by introducing them into the mixing chamber 4 through the conduit 6, the object being not only to reprocess the polymers but also to mix the residue from such reprocessing with the tars from the cracked and reduced charges also entering the fractionating column. With this in mind, it will be observed that the cracked charge from the pipe 2, the reduced crude charge from the pipe 5, and the charge of hot polymers from the pipe 6, all enter the mixing chamber 4. The hot polymers, entering the mixing chamber at about 300° F., serve to further reduce the average temperature of the charge through the pipe 7 into the fractionating column. It is desirable that the temperature of the fluid entering the fractionating column be not too high, and it has been found that while the above temperatures are approximate, they result in a very satisfactory charge entering the fractionating column.

The fractionating column is indicated generally at 3 and contains the vaporizer section 10,

the accumulator section 11 and the fractionating section 12. These sections are preferably of standard type and the vapors rise in this column to the cap 13 thereof where they escape through 5 the pipe 14. The heavier fractions will fall by gravity into the base 15 of the fractionating column and may be withdrawn through the pipe 16 as a suitable fuel oil.

As previously indicated, the fuel being drawn 10 off from the base 15 is an improved grade of fuel oil over that now generally obtained, because the heavier fractions falling to the base of the column contain not only the tars from the crude charges but also a percentage of gums from the 15 hot polymers which are being reprocessed. This combination of gums and tars provides an improved fuel oil which is one of the products of the present system.

The fractions discharging from the fractionating 20 column through the pipe 14 pass to the junction point 20 of the pipes 21 and 22. The junction point 20 is preferably positioned in the pipe 14 so that the pipe 22 extends away from the junction in a vertically downward direction; 25 thus the heavier fractions will tend to flow into the pipe 22 while the lighter fractions will pass into the pipe 21. A suitable valve 23 controls the pipe 21.

This valve is known as an equalizer valve and 30 may be adjusted to obtain the desired pressure differential. It is intended that the pressure in the reactivating tower 34 will be slightly greater than the pressure in the reflux drum 27. This causes the heavier fractions to pass into the pipe 22 and the lighter fractions to pass into the pipe 21.

The apparatus indicated generally at 25 comprises a set of condensers for condensing the heavier fractions which have passed into the pipe 40 22 from the junction 20. From the condenser 25 these heavier fractions enter the reflux drum 27 where a separation of the liquids and the vapors is made. It is intended that a constant level 45 of liquid and a substantially constant vapor pressure will be maintained in this drum. To accomplish this, a float control is indicated generally at 28 and may be of any well known type. This float control serves to maintain a balanced pressure in the reflux drum.

50 It seems obvious that the lighter fractions from the reflux drum 27 will pass into the pipe 30 and escape into the system in a manner which will be later described. The liquids in the reflux drum, however, are to be recirculated in the system and with this in mind the pump 31 has been provided. This pump 31 conveys the liquids thru the pipe 32 where the liquid enters the top of the fractionating column as at 33. It will be appreciated that the temperature of this liquid 55 entering the point 33 is considerably lower than the temperature of the top of the fractionating column. It is intended that the pump 31 will be connected to a thermostat or suitable thermocouple in the top 13 of the fractionating column. 60 This thermostat will control the operation of the pump 31 so that it will discharge at the point 33 a sufficient volume of the cooled heavier fractions to maintain a constant temperature in the top of the fractionating column.

65 Thus, if a 400° F. end point gasoline is required, the control of the pump 31 will be set to vary within approximately a 1/2° of the temperature on either side of the desired end point. The discharge of these heavier fractions into the 70 light vapors in the fractionating column causes

the heavier fractions to be reprocessed and some additional yield obtained therefrom. With this construction a very accurate end point can be maintained and at the same time the heavier fractions are being refluxed through the system. 5

The lighter fractions, having been separated at the junction 20, flow through the pipe 21 and enter the reactivating tower 34. A suitable steam inlet 35 may be connected into the line 21 if desired. 10

The reactivating tower 34 is provided in order to polymerize the fractions there entering and to remove the objectionable constituents in order to obtain a more perfect fuel. With this in mind, the reactivating tower 34 embodies a housing 36, 15 which is arranged to contain a quantity of clay or suitable filter 37. This body of clay is preferably supported by means of a base 38, which in turn supports a filter or screen 39. A discharge pipe 40 serves to remove the charge of clay when the same is to be removed or replaced. 20

The pipe 21 is indicated at the top of Fig. 1, and it is through this pipe that the vapors enter the housing 36. The major portion of the vapors entering the housing 36, however, pass 25 through a body of clay 37 into the chamber 44, at the base of the housing. It is contemplated that there will be two outlets from the base of this housing, a pipe 45 leading to the refractionating column for the lighter of the polymers obtained after the passage of the vapors through the clay body, and, second, an outlet 46 leads to the base of the final refractionating column 43, so that the heavier polymers will be discharged 30 near the base of the refractionating column. 35

The filter or screen 39 disposed on the base 38 may be of any desired form such as Monel metal, rock wool or other suitable material.

In the system as here practiced it is contemplated that the body of clay 37 within the reactivating tower may be re-washed when desired by circulating a flow of liquid through the pipe 50 from the gas separator 51 by means of a pump 52. The liquid forced through this pipe 50 by the pump 52 is a portion of the finished gasoline 40 which has passed completely through the system. The object of drawing off a portion of this finished product is twofold, one being to control the temperature in the top of the reactivating tower 34 by introducing the desired volume of gasoline which is much cooler than the temperature of the reactivating tower, because this gasoline has passed through the refractionator and the gas separator. The pipe line 53 is shown as 45 entering the top of the reactivating tower 34. 50

The other purpose of refluxing a quantity of gasoline in this manner is to provide for washing the body of clay 37 within the tower. Thus, if the clay becomes clogged to any extent wherein it is not functioning satisfactorily, then the pump 52 may be set in operation and the clay can be flushed with a rich mixture of gasoline which will 55 wash out the gums deposited in the clay and prolong the service obtainable from the clay. The gums carried out of the clay by the gasoline pass into the base and through the pipe 45 or 46 into the final refractionating column, as heretofore described. It seems obvious that this is merely a refluxing operation which tends to prolong the service obtainable from a charge of clay in the reactivating tower and at the same time control the temperature of the clay tower. 60

The liquid from the pump 52 also serves to control the temperature in the top of the final refractionating tower. This is accomplished by 65

means of the branch pipe 54, which leads off from the pipe 50 and enters the top of the refractionating column 43, as at 55. The valves 56 and 57 control the pipes 53 and 54, respectively. The adjustment of these valves controls the flow of gasoline through the pipe 50, so that the temperature of the clay tower and the refractionating column may be accurately determined. Gasoline flowing into the top of the refractionating column 43, not only serves to cool the rising vapors in the refractionating column, which is in the form of a bubble tower so that the lighter vapors will rise to the top and the heavier vapors will sink to the base 60 thereof, but, also, serves to wash the rising vapors and prevent carrying over of the lighter polymers. The lines 61 indicate the baffles or plates which are usually provided in bubble towers of this type.

The heavier gums and polymers from the reactivating tower will accumulate in the base 60 and one of the most important features of this invention is the reprocessing of these polymers thrown off from the base 60. To accomplish this a pump 61 is provided which discharges into the line 6, which has been previously described as entering the mixing chamber 5. The return of these polymers to the entering charge increases the yield of gasoline because the polymers are again introduced into the fractionating column 3, as at 74. In this manner the rich gasoline is caused to bubble through the lean oil so that the lean oil will absorb the gasoline from the rich gas and the gas thus dried will escape from the absorber through the pipe 79. Control of the flow through the pipe 79 will be had by the valve 80.

The discharge from the final refractionating column 43 will be a gum-free product and occurs through a pipe 63. This pipe is connected to the condensers 64 to condense the vapors from the refractionating column, so that the gasoline will enter the separator 51 through the pipe 65. This gasoline entering the separator 51 contains a percentage of what is known as fixed gas which is separated from the liquid in this separating tower. The gas separated in this tower escapes through the discharge pipe 66, whereas the liquid or finished product gasoline flows out through the run down pipe 67 to a suitable storage or for consumption as a finished product. A bypass line 68 is provided on the side of the separator so that any desired level may be maintained within the separator.

The pipe 66 joins the pipe 30 previously described and these two pipes are combined in a conduit 69, it being understood that the vapors

passing into the pipe 69 are very rich in gasoline because the product in the pipe 30 has escaped from the top of the reflux drum and the product in the pipe 66 is the separated gas from the gasoline. Before discharging this fixed gas from the system it is desirable to remove the gasoline therefrom and with this in mind the pipe 69 enters the base 90 of the gasoline absorber 71. This may be in the form of a bubble tower also, and it is intended that there will be maintained in this absorber a circulation of lean oil which is drawn off from adjacent the top of the fractionating column. This lean oil will be circulated through the absorber as a counter-current to the rising gases from the base 70 of the absorber. To provide for this circulation a pipe 72 is shown as entering the top of the absorber and this pipe 72 is shown as entering near the top of the fractionating column 3, as at 74. In this manner a quantity of lean oil will enter the top of the absorber and flow by gravity to the base 70 thereof where it will be drawn off by the pump 75 and forced into the pipe 76, which is shown as entering the fractionating column 3, as at 77. In this manner the rich gasoline is caused to bubble through the lean oil so that the lean oil will absorb the gasoline from the rich gas and the gas thus dried will escape from the absorber through the pipe 79. Control of the flow through the pipe 79 will be had by the valve 80.

While the apparatus illustrated in the drawing herewith is more or less diagrammatic, it is intended that any desired apparatus may be used in practicing the invention which broadly contemplates reprocessing of the polymers and refluxing the fractionating and reactivating towers in order to increase the yield of gasoline and to provide an improved grade of fuel oil while maintaining an accurate control of the temperatures in the column.

What we claim as new is:

A process of increasing the yield of gasoline from hydrocarbons which comprises fractionating the cracked crude oils, leading off the lighter constituents of the fraction thus obtained to a reactivator, passing the heavier constituents back to the top of the fractionating column to control the end point, reactivating the lighter constituents, refractionating the reactivated fluid and drawing off the accumulated polymers, refluxing the polymers so drawn off by introducing them into the cracked charge entering the process, introducing with the cracked charge and the polymers a charge of reduced crude oil to control the entrance temperature of the composite charge.
